UNITED STATES PATENT OFFICE.

FREDERICK G. FOLBERTH AND WILLIAM M. FOLBERTH, OF CLEVELAND, OHIO, AS
SIGNORS TO TRICO PRODUCTS CORPORATION, OF BUFFALO, NEW YORK, A COR-
PORATION OF NEW YORK.

WINDSHIELD CLEANER.

Original application filed March 20, 1924, Serial No. 700,659. Divided and this application filed January 24, 1925. Serial No. 4,607.

This invention relates to windshield cleaners, and more particularly to suction operated cleaners adapted to be operated by the suction of the intake manifold of an internal combustion engine.

This application is a division of our co-pending application for windshield cleaners, filed March 20, 1924, Serial No. 700,659. In the said application, we have described a motor casing construction, and the valve mechanism forming the subject matter of the present application, but the claims of the said application are limited to the motor casing construction.

An object of the invention is to provide a cylinder construction comprising two halves or sections of a cylinder and clamping means for securing the two sections to each other. More specifically, we provide a cylinder formed in two sections, each section of which is provided with a cylinder head at its outer end and is provided with a flared edge at its inner end and a grooved clamping member adapted to surround the contacting flared inner ends of the cylinder sections to secure them to each other.

A further object of the invention is to provide improved valve shifting mechanism for a motor of this character.

A still further object of the invention is the provision of valve shifting mechanism consisting of a pivoted member adapted to be swung on its pivot by a moving part of a motor, a spring connected to said pivoted member and adapted to be maintained under tension, and a valve supporting member adapted to be engaged by said pivoted member to automatically shift the valves of the cleaner motor.

In the accompanying drawings, we have shown one embodiment of the invention. In this showing:

Figure 1 is a perspective view of a windshield cleaner,

Figure 2 is a vertical transverse sectional view through the cleaner when in position on a windshield,

Figure 3 is a perspective view of one of the sections of the cylinder,

Figure 4 is a vertical sectional view substantially on line 4-4 on Figure 2, showing the valve shifting member,

Figure 5 is a similar view substantially on line 5-5 of Figure 2, showing the manner in which the valve shifting member is engaged by a movable part of a motor,

Figure 6 is a horizontal sectional view through a portion of the cylinder and closure member showing the passages in the closure member,

Figure 7 is an exterior elevation of the closure plate, parts being shown in section,

Figure 8 is a detail view of the valve shifting mechanism, and,

Figure 9 is a similar view of the clamp.

Referring to the drawings, the reference numeral 1 designates a windshield frame of the usual construction having a pane of glass 2 or other transparent material arranged therein. The cleaner motor, shown as a cylindrical casing, is designated generally by the reference numeral 3, and is adapted to be arranged on the interior of the windshield frame, as shown. The motor is provided with a transverse power shaft 4, adapted to be oscillated and the outer end of this shaft is adapted to receive a cleaner arm 5. The shaft is provided with a transverse passage for the reception of the end of the cleaner arm which is secured against displacement by a set screw 6. A nut lock 7 is arranged on the set screw. This, however, forms no part of the present invention, it being disclosed and claimed in our prior Patent No. 1,472,644, granted October 30, 1923. The lower end of the cleaner arm is provided with a suitable retaining device or holder 9 and a cleaner element is arranged in this holder. The cleaner element consists of a backing strip 10 of metal or other suitable material and a rubber strip 11 adapted to engage the surface of the windshield to be cleaned.

As stated, the motor casing is formed in two sections, one of which is shown in detail in Figure 3 of the drawings. Each section of the motor casing consists of a tubular portion 12 having a closed end 13 adapted to form one of the cylinder heads. The other end of the cylinder section is flared, as indicated at 14 and is further provided with a recess or cut-out portion 15 for the reception of the closure plate on which the valve mechanism is mounted. Opposite the cut-out por-

tion 15, the end of the cylinder section is provided with a semi-circular portion 16 and the two semi-circular portions are adapted to align with each other, forming a bearing for the reception of the power shaft. As shown in Figure 2 of the drawings, the power shaft projects through the cylinder and the handle 17 is adapted to be arranged thereon, the handle being secured to the shaft by means of a set screw 18.

A closure plate 19 is arranged intermediate the ends of the cylinder, the plate being curved in cross section to conform to the cylinder wall, as shown in Figure 1 of the drawings. This plate extends over a portion of the exterior of each section of the cylinder wall, and is provided with an inwardly extending projection 20 adapted to be received in the recess 15. The upper portion of the plate is provided with a lug or projection 21 adapted to be received in an opening 22 formed in a substantially semi-circular clamping member 23. The detail construction of the clamping member is shown in Figure 9 of the drawings. As shown, it is adapted to extend around the cylinder at the point where the two sections are connected to each other and from the top of the closure plate to the bottom. This clamping member is provided with a substantially V-shaped groove 24 adapted to receive the flared ends 14 of the cylinder sections and thus clamp them to each other. The lower end of the clamping element is provided with ears 25 having openings 26 for the reception of screws or other fastening elements which are received in threaded openings in the closure plate.

Within the cylinder, we provide a pair of spaced pistons, each of which comprises a plurality of disks 27 of metal or other suitable material having a packing strip 28 arranged between them. This packing strip is of larger diameter than the diameter of the cylinder, forming a flange 29. The parts of the piston are secured to each other by a bolt 30, passing through openings in the metal plates. The two pistons are connected to each other by means of a connecting member 31 having offset ends 32. These offset ends are provided with openings for the reception of the bolts 30. Intermediate the offset ends, the connecting member is provided with spaced openings 33, forming a rack. A segmental gear 34 is mounted on the power shaft and this gear is provided with teeth 35 adapted to mesh with the rack. The upper portion of the gear is provided with an arcuate surface 36 curved on a radius from the center of the shaft, and at each end of the arcuate portion, there is provided a shoulder 37.

The closure plate is provided with a pair of longitudinally extending passages 38, communicating with transverse passages 39

extending through the thickened portion 20 to the interior of the cylinder. The outer ends of the passages 38 are connected to conduits 40 which extend longitudinally of the cylinder and communicate with the opposite ends thereof through openings 41 (see Figure 4). The closure plate is further provided with a passage 42, having a tube 43 arranged in its outer end. This tube is adapted to receive a suitable conduit (not shown) which is adapted to be connected to the intake manifold of an internal combustion engine (not shown) or other suction producing means. Intermediate the ends of the closure plate, the passage 42 communicates with an angularly disposed passage 44. As shown, the passage 44 is reduced in size adjacent its upper end and is provided with a valve seat 45'. The lower portion of the passage is threaded and is adapted to receive a threaded valve stem 46, having a valve 47 formed on its upper end. The valve stem projects from the closure plate and is provided with a knob or handle 48. The upper end of the inclined passage 44 communicates with a transverse suction passage 45 arranged between the passages 39 (see Figure 6).

The suction passage 45 is adapted to be connected to either of the passages 39 and a suitable automatic valve mechanism is provided to alternately connect the passages 39 to the suction passage 45 to reciprocate the pistons in the cylinder. As shown, a pin 49 is arranged on the inner face of the closure plate and extends inwardly therefrom. This pin is adapted to support a valve shifting member. The valve shifting member comprises a main portion 50, pivotally mounted on the pin 49 adjacent its lower end and curving upwardly. The upper end of this member is provided with an angular extension 51 adapted to be arranged over the arcuate portion 36 of the segmental gear. Adjacent the bottom, the valve shifting member is provided with a loop 52 and an arm 53 extends upwardly from this loop. The arm is pivotally mounted on the pin 49 whereby the valve shifting member is supported at two points. The upper portion of the arm 53 is provided with an arcuate face 54, curved on a radius from the center of the pin 49 and shoulders 55 are arranged at the opposite ends of this arcuate face. A coil spring 56 is connected at one end of the loop 52 and the other end of the spring is connected to a pin 57 mounted on the inner face of the thickened portion 20 of the closure member. A valve supporting member 58 is arranged adjacent the valve shifting member. As shown, the valve supporting member is provided with an opening 59 adapted to receive a pin 60 carried by the closure member adjacent the top of the cylinder to pivotally support this member.

The valve supporting member is further provided with a central cut-out portion 61, adapted to loosely surround a sleeve 62 extending inwardly from the closure member 5 and receiving the shaft 4. The valve supporting member is provided with a projecting finger 63 which is arranged above the arcuate face 54 of the valve shifting member and is adapted to engage the shoulders 10 55. A valve 64 is mounted on the opposite side of the valve supporting member or carrier to move over the inner face of the thickened portion 20 of the casing part 19 as a valve seat, the valve being cup or dish shaped and being adapted to extend over the suction passage 45 and one of the connecting passages 39 to establish communication between the source of suction and one 15 end of the cylinder, as shown in Figure 6 of the drawings. This valve is provided with a stem 65 passing through an opening 66 in the valve supporting member. The lower end of the valve supporting member is provided with spaced projections 20 67 which are arranged on opposite sides of the pin 49 to limit the movement of the valve supporting member to properly position the valve each time it is moved.

In operation, the manually controlled valve 47 is opened when operation of the cleaner is desired, by turning the knob 48 and the cleaner motor is then placed in communication with the source of suction or pressure. In Figure 4 of the drawings, the 30 valve shifting member is shown moved to the right and the valve is then in a position to connect the right end of the cylinder to the source of suction. The left end of the cylinder is in communication with the atmosphere through the left tube 40, the uncovered duct 39 into the space between the pistons, and thence through the unpacked joint between the casing sections 12 and the clamping band 23. The pistons then move 40 toward this end of the cylinder, oscillating the gear and shaft in a counter clockwise direction. As the gear moves, the shoulder 37 at the right of the cylinder moves toward the angular extension 51 of the valve shifting member. As the pistons approach their 45 limit of movement, the shoulder engages the angular extension to move the valve shifting member in a counter clockwise direction. The initial movement of the valve shifting member is by contact with the shoulder 37 and is at the same speed as the speed of the gear. During this movement, the left shoulder 55 of the arm 53 moves away from the finger 63 of the valve supporting member 60 and the right shoulder approaches it. The spring 56, connected to the loop 52 is initially under tension tending to draw the lower end of the valve shifting member in a counter clockwise direction and the valve shifting member is shown at its limit of

movement in this direction. A line connecting the ends of the spring is then below the pin 49. As the valve shifting member moves in a counter clockwise direction, the line connecting the ends of the pin moves upwardly 70 above the pin 49 and the valve shifting member is then snapped or shifted to its other position. Substantially at the instant when the valve shifting member is snapped to its second position, the right shoulder 55 of the arm 53 engages the finger 63 to shift the valve supporting member and the valve. The valve is thus positively shifted with a snap or quick action and the possibility of the valve stopping on dead center is eliminated. The movement of the valve supporting member is limited by an engagement of the shoulders 67 and the pin 49. The opposite end of the cylinder is then connected to the source of suction and the pistons move in the opposite direction to turn the shaft and the segmental gear in a clockwise direction. The operation of shifting the valves when moving in this direction, is substantially the same as that heretofore described and repetition is deemed unnecessary.

It is to be understood that the form of our invention herewith shown and described is to be taken as a preferred example of the same, and that various changes in the shape, size, and arrangement of parts may be resorted to without departing from the spirit of the invention or the scope of the subjoined claims.

We claim:

1. In a motor comprising a casing, a movable member arranged in said casing and adapted to be actuated by differential pressure, and valve mechanism to alternately connect said casing on opposite sides of said movable member to a source of differential pressure, said valve mechanism comprising a pivoted valve shifting member, said member being provided with an angular extension adapted to be engaged by said movable member, an arm laterally offset from and carried by said valve shifting member, said arm being provided with spaced shoulders, a valve supporting member adapted to be alternately engaged by said shoulders, a valve carried by said supporting member, and a spring fixed at one end and secured to said valve shifting member between the main body portion of the latter and said laterally offset arm to shift said valve shifting member to either of two positions.

2. A device constructed in accordance with claim 1 wherein said valve supporting member is arranged alongside of said arm and has a finger struck out between said shoulders and adapted to be alternately engaged by said shoulders.

3. A motor comprising a casing, a movable member mounted in said casing, a segmental gear meshing with said movable

member, and means for alternately establishing a differential pressure on opposite sides of said movable member, said means comprising a pivoted valve shifting member having an angular extension, said segmental gear being provided with a pair of spaced shoulders adapted to alternately engage said extension to shift said valve supporting member, an arm carried by said valve shifting member, said arm being provided with an arcuate surface and a shoulder at each end of said surface, a valve supporting member arranged adjacent said arm, a finger extending from said valve supporting member over said arcuate surface and adapted to be engaged by one of said shoulders when said valve shifting member is moved, a valve carried by said supporting member, and a spring secured to said valve shifting member and adapted to shift it to either of two positions.

4. A device constructed in accordance with claim 3, wherein said valve shifting member is mounted on a pin extending through it adjacent one end and said arm is connected thereto by means of a loop, said spring being secured to said loop.

5. A device constructed in accordance with claim 3, wherein said valve shifting member comprises a main body portion arranged substantially parallel to said arm and connected thereto by a loop, said arm and said main body portion being provided with aligned openings for the reception of a pivot pin, said spring being connected to said loop.

6. In a fluid pressure motor, a casing having a shaft bearing, a shaft in the bearing, a piston movable in the casing, a member rockable by the piston and carried by the shaft for rocking the latter, said member having spaced shoulders on one side of the shaft, valve mechanism for operatively admitting operating fluid pressure to the casing and including a valve shifting member pivotally mounted at the opposite side of the shaft from said shoulders and extending about said shaft and between said shoulders for engagement with and operation by said shoulders, a movable valve carrier having a play connection with said shifting member for being operated thereby, and resilient means acting quickly to move said shifting member after the latter has been moved a

predetermined distance by either of said shoulders.

7. In a fluid pressure motor, a casing part having a shaft bearing and an adjacent valve seat, a shaft journaled in the bearing for rocking movement, a pivot pin arranged on said casing part, a valve on the valve seat, a carrier for the valve movable back and forth for shifting the valve to two positions on the valve seat, said carrier having spaced shoulders on opposite sides of the pivot pin for engaging the same to limit its valve-shifting movements, a shifting member pivoted on said pivot pin and rockable by and during the rocking of said shaft, said shifting member having a laterally offset arm also pivoted on said pivot pin and arranged adjacent said valve carrier, a play connection between said carrier and arm and permitting limited independent movement of said shifting member during which said shifting member is actuated from said shaft, and a spring anchored at one end to one side of said pivot pin and being arched about the latter is connected to said shifting member at a point on the opposite side of said pivot pin for movement under tension to opposite sides of the plane which includes said pivot pin and the anchored end of said spring.

8. In a fluid pressure motor, a casing part having a valve seat, a valve on the seat, a carrier for the valve pivoted at one end on the casing part to move the valve on its seat, the free end of said carrier having spaced shoulders, a shifting member pivoted on said casing part with its pivot extending between said shoulders for engagement thereby to limit the movement of said carrier, said shifting member being rockable on its pivot by a moving part of the motor and having an arm extending alongside of said carrier toward the pivoted end thereof, a play connection between said arm and said carrier for permitting limited relative movement thereof, and spring means acting to accelerate the rocking movements of said shifting member which are initiated by said moving part of the motor.

In testimony whereof, we affix our signatures.

FREDERICK G. FOLBERTH.
WILLIAM M. FOLBERTH.
